(57) CLAIM

The ornamental design for a golf bag bottom, as shown and described.

DESCRIPTION

FIG. 1 is a top perspective view of a golf bag bottom showing my new design;

FIG. 2 is a bottom perspective view of the golf bag bottom of FIG. 1;

FIG. 3 is a rear view of the golf bag bottom of FIG. 1;

FIG. 4 is a front view of the golf bag bottom of FIG. 1;

FIG. 5 is a top view of the golf bag bottom of FIG. 1;

FIG. 6 is a bottom view of the golf bag bottom of FIG. 1;

FIG. 7 is a left view of the golf bag bottom of FIG. 1; and,

FIG. 8 is a right view of the golf bag bottom of FIG. 1.

The broken lines shown in one or more of the figures are for illustrative purposes only and form no part of the claimed design.

1 Claim, 6 Drawing Sheets
